UNITED STATES PATENT OFFICE.

EDWARD G. WATKINS, OF GARDNER, MASSACHUSETTS.

DESIGN FOR CANE FABRIC.

SPECIFICATION forming part of Design No. 26,477, dated December 29, 1896.

Application filed November 27, 1896. Serial No. 613,708. Term of patent 7 years.

To all whom it may concern:

Be it known that I, EDWARD G. WATKINS, of Gardner, in the county of Worcester and State of Massachusetts, have invented and produced a new and original Design for Cane Fabric, of which the following is a specification.

Reference is to be had to the accompanying drawing, forming a part of this specification, which shows a piece of cane fabric with my design applied.

The leading feature of my design consists in the bars or strips *a* of contrasting color from the body of the fabric and broken alternately upon its sides and in its center to show the body of the fabric in the form of checks or squares.

f represents a piece of cane fabric bearing

my design, which consists of the stripes or bars *a* of a contrasting color from the body ²⁰ of the fabric. These stripes are broken alternately upon the margin and at the center to show the body of the fabric and produce the appearance of a checked stripe.

I claim—

The design for cane fabric, as herein shown and described.

In testimony whereof I have signed my name to this specification, in the presence of two subscribing witnesses, this 18th day of ³⁰ November, A. D. 1896.

EDWARD G. WATKINS.

Witnesses:

HENRY M. COLLESTER,
THATCHER B. DUNN.
